UNITED STATES PATENT OFFICE.

CARL T. ANDERSON, OF ELMHURST, ILLINOIS, ASSIGNOR TO WEBSTER MFG. COMPANY, OF CHICAGO, ILLINOIS, A CORPORATION OF OHIO.

CRUSHING MACHINE.

Application filed January 7, 1922. Serial No. 527,802.

To all whom it may concern:

Be it known that I, CARL T. ANDERSON, a citizen of the United States, and a resident of Elmhurst, Du Page County, Illinois, 5 have invented a certain new and useful Improvement in Crushing Machines, of which the following is a specification.

This invention relates to crushing machines in general, but more particularly to 10 those in which a pivoted breaker plate is opposed to a rotary crushing roll, so that a hopper like space is formed between them to receive the materials to be crushed, and whereby a throat is formed at the bottom 15 of said space for the discharge of the product during the operation of the machine.

Generally stated, the object of the invention is to provide a novel and improved construction whereby both relatively long and 20 relatively short teeth may be employed on the crushing roll, and whereby, in a crusher of this type, the said breaker plate is desirably set back far enough from the crushing roll to entirely clear the said long teeth, 25 thus widening said throat, and whereby in order to insure the desired size for the product the throat is then contracted in the desired manner by means projecting outward from the breaker plate and between said long teeth and into operative relation to said short teeth, as will hereinafter more fully appear.

Another object is to provide an improved construction and arrangement whereby certain features and certain expedients heretofore considered necessary or desirable are 35 eliminated and rendered unnecessary in the construction of a crusher of this particular character, thus obviating the necessity of using certain things heretofore considered 40 important and necessary, in order to insure the desired crushing action, as will also hereinafter more fully appear.

It is also an object to provide certain 45 details and features of construction tending to increase the general efficiency and the serviceability of a crushing machine of this particular construction.

To the foregoing and other useful ends, 50 therefore, the invention consists in matters hereinafter set forth and claimed and shown in the accompanying drawings in which—

Figure 1 is a side elevation of a crusher

embodimenting the principles of the invention, showing certain portions broken away to 55 show the relative arrangement of the rotary crushing roll and the pivoted breaker plate.

Figure 2 is a plan of said crusher.

Figure 3 is a vertical section on line 3—3 in Figure 1. 60

Figure 4 is a section on line 4—4 in Figure 1.

As thus illustrated, the invention comprises a body frame 1 of any suitable or desired character, having a transverse driving shaft 2 which is gear-connected by the gears 3 and 4 with the axis 5 of the relatively large crushing roll 6 which is disposed within the interior of said body frame. Said roll is provided with removable segments or 70 outer sections 7 which are held in place by bolts 8 in any suitable or desired manner. The relatively short teeth 9 are integral with said segments 7, while the larger teeth 10 are separately formed and are inserted 75 through the segments and have their inner ends 11 riveted over, these relatively large and small teeth being of any suitable or desired form and being arranged on the roll in the manner shown, so that they extend 80 outward from the roll toward the pivoted breaker plate 12 which is mounted to swing about a transverse axis 13 at its upper end. Said breaker plate is provided with a removable wearing face or section 14 which is 85 held in place by bolts 15 in any suitable manner. A transverse pin or axis member 16 is inserted through the lower end portion of the breaker plate, and rollers 17 are mounted on this pin or member 16, said 90 rollers being spaced apart by the portions 18 of the breaker plate. Rods 19 have their ends supported on the outer ends of the member 16 and are arranged to slide or reciprocate in guides 20 on the body frame, coil 95 springs 21 being interposed between said guides and the nuts on the outer ends of said rods.

It will be seen that the breaker plate 12 is set back far enough from the crushing roll 100 6 to entirely clear the long teeth 10 on said roll, so that the throat is somewhat widened at the bottom of the hopper like space formed between the crushing roll and the breaker plate to receive the materials to be 105 crushed. The rollers 17, however, project

back toward the roll 6 from the breaker plate, and extend between the teeth 10 and into operative relation to the teeth 9, as shown, thereby to insure a product of the desired size. The two kinds of teeth, in combination with the rollers 17, tend to insure the desired crushing action, and said rollers tend to reduce friction between the materials and the breaker plate. The breaker plate can yield, when necessary, by compression of the springs 21, thereby to insure against breakage in case of hard lumps in the materials. The large teeth 10 do not extend into the breaker plate, in any sense whatever, and this construction and arrangement obviates the necessity of slotting or recessing the breaker plate to provide clearance for the teeth 10, inasmuch as the breaker plate is set back the full distance necessary to keep it from engaging the long teeth 10 during the operation of the machine. The pressure on the rollers 17 is communicated directly to the tension rods 19, through the pin or axis member 16, and by means of these rollers the throat of the hopper like space is contracted to insure the desired size for the product. The breaker plate face 14 is immediately above the rollers 17, and can be taken off when worn or impaired by the crushing action. Also, of course, the segments 7 can be removed when the teeth are worn or impaired, and new segments can be secured in place. It will be understood, of course, that the crushing roll 6 rotates in a direction to carry the materials downward and to force them through the throat at the bottom of the hopper like space between this roll and the breaker plate.

From the foregoing it will be seen that the pressure exerted by the materials against the rollers 17 is communicated directly through the axis member 16 to the rods 19, and in case of lumps or hard spots in the materials the rods 19 will move endwise, thereby compressing the springs 21, and these springs will then return the rollers 17 to their normal position in operative relation to the short teeth 9 on the main rotary crushing roll. Thus the flat face of the breaker plate 12, as shown occupies a normal position a greater distance from the roll, or greater than in the ordinary construction, so that without the rollers 17 the throat at the bottom of the hopper like space would be too wide for the desired product. Therefore, as shown and described, the rollers 17 are employed to contract the throat in the desired manner, thus obviating the necessity of setting the breaker plate up closer to the crushing roll having the teeth thereon, and insuring a wider hopper above the throat. The long teeth 10 do not pass through the face of the breaker plate, but pass between the rollers 17 which project outward from said face. In the structure shown and de-

scribed, the axis member 16 which carries the rollers 17 is supported by the swinging member forming the breaker plate 12, but it is obvious that the member 16 can be supported in any suitable or desired manner to present the rollers 17 (by the yielding action of the springs 21) to the shorter teeth on the surface of the larger crushing roll, so that the materials are forced between rolls to produce the crushing action.

As shown and described, there are some short teeth 9 which are in line circumferentially with the long teeth 10, and there are other short teeth 9 disposed on said roll in line with the rollers 17 on the breaker plate. Thus there are some short teeth on the roll in line with projecting means on the breaker plate, and there are some long teeth on the roll which extend between said projecting means on the breaker plate, and there are other short teeth disposed on the roll in line circumferentially with said long teeth. This tends to produce a powerful crushing action, and tends to produce a product of the desired character.

As shown in Figures 1 and 4 clearance is provided between the roll 6 and the section 7, for the riveted over heads 11 of the inner ends of the longer teeth 10, whereby these fastening means 11 are not accessible except when the sections 7 are removed from the roll. The bolts 8, however, are accessible inside of the roll as shown, so that the sections may be removed. If a long tooth 10 breaks, the section bearing this tooth can be removed, by loosening the bolts 8, and then the riveted over head 11 can be cut off with a cold chisel, if necessary, to remove the broken long tooth. But, as shown and described, the clearance shown in the drawings for the fastening means 11 is sufficient to permit the sections to be clamped tightly against the outer surface of the roll 6, as shown, with the ends of the sections tightly together.

What I claim as my invention is:—

1. In a crusher, the combination of a roll, a breaker plate disposed in operative relation to said roll, forming a hopper-like space with a discharge throat between the roll and the plate to receive the materials to be crushed, relatively short teeth on the roll, relatively long teeth on said roll, with said plate set back far enough from the roll to clear said long teeth, thus widening said throat to prevent the long teeth from passing through the face of the plate, and movable means projecting outward from said plate and between said long teeth and into operative relation to the ends of said short teeth, forming a contraction of said throat, whereby to crush said materials in said space and discharge the product from said throat in the operation of the crusher.

2. A structure as specified in claim 1, said

- projecting means comprising a plurality of rollers spaced apart to receive said long teeth between them and mounted to rotate about a common transverse axis on said breaker plate.
3. The structure as specified in claim 2, said projecting means being rotatable about a transverse axis on the breaker plate.
4. The structure as specified in claim 1, 10 said breaker plate having a removable wearing face section thereon immediately above said projecting means.
5. In a crusher, the combination of a roll, a breaker plate opposed to said roll, forming a hopper-like space between them for receiving the materials to be crushed, with a discharge throat at the bottom of said space for discharging the product during the operation of the crusher, movable means 15 projecting outward from and beyond the face of said plate and into operative relation to said roll, thereby contracting said throat to produce the desired crushing action, and means for mounting said plate for 20 movement toward and away from said roll.
6. A structure as specified in claim 5, said means projecting from the plate comprising a plurality of rollers mounted to rotate about a transverse axis on said plate.
- 30 7. A structure as specified in claim 5, in combination with teeth on said roll to cooperate with said plate and the projecting movable means thereon to produce the desired crushing action.
- 35 8. A structure as specified in claim 5, said projecting means comprising a transverse axis for the rotation thereof during the operation of the crusher.
9. In a crusher, the combination of a pivoted breaker plate, one or more rollers forming means projecting from said plate, and means opposed to said plate and forming therewith a hopper like space to receive the materials to be crushed.
- 40 45 10. A structure as specified in claim 9, in combination with means to pivot said plate to swing about a transverse axis extending parallel with the axis of said rollers.
- 50 11. A structure as specified in claim 9, in combination with means whereby said plate is yieldingly presented in operative position to yield under pressure exerted by the materials in said space.
- 55 12. In a crusher, a cylindrical member forming a crushing roll, having the outer surface thereof composed of removable sections, and having some teeth formed integral with said removable sections, and other teeth formed separately and inserted 60 through said removable sections and rigidly secured therein, these other teeth being fastened in place by means on the back of each section, with clearance between the roll and the inner surface of each section for said fastening means, whereby said fastening 65 means are inaccessible, so that said other teeth must be secured in place before the sections are fastened on the roll, and whereby removal of the sections is necessary for the removal of the other teeth, in combination 70 with crushing means co-operating with said teeth to crush the materials, and means accessible inside of the roll to fasten the sections in place.
13. A structure as specified in claim 12, 75 said integral teeth being shorter than said teeth which are separately formed, and the longer teeth being inserted through the sections and upset or riveted over at their inner ends to permanently hold them in 80 place.
14. A structure as specified in claim 12, 85 said means comprising a pivoted breaker plate having means projecting outward from the face thereof to extend between said teeth which are separately formed and into operative relation to said integrally formed teeth.
15. A structure as specified in claim 1, 90 said projecting means comprising a plurality of rollers spaced apart to receive said long teeth between them, an axis member for said rollers, tension rods connected to the outer ends of said axis member, springs on said tension rods, and guides engaging 95 said springs, whereby said breaker plate and said rollers are yieldingly presented to said first mentioned roll.
16. A structure as specified in claim 5, 100 said projecting means comprising rollers, an axis member for said rollers, and spring held tension rods connected to said axis member.
17. A structure as specified in claim 9, in 105 combination with tension rods connected to the axis of said rollers, whereby the breaker plate is yieldingly held in operative position.
18. In a crusher, a transverse axis member, rotary means free to turn in either direction on said axis member, means co-operating with said rotary means to crush the materials, a breaker member to movably support said axis member, and end-wise movable tension rods connected to the outer 110 ends of said axis member, whereby said rotary means are yieldingly maintained in operative position.
19. In a crusher, a roller mounted to rotate freely in either direction about a horizontally disposed axis, crushing means opposed to said roller, means for operating said crushing means, so that the materials pass downward between said roller and said crushing means, supporting means to movably support said roller to permit said axis thereof to move toward and away from said crushing means, said supporting means co-operating with said crushing means to form 115 a hopper, and spring means to yieldingly 120 support said roller.
- 60 65 70 75 80 85 90 95 100 105 110 115 120 125 130

resist movement of the roller away from said crushing means.

20. In a crushing machine, the combination of a breaker plate, a rotary crusher roll, means projecting from the breaker plate toward the roll, long teeth on said roll to extend between said projecting means on the breaker plate, in close relation to the face of said breaker plate, and short teeth

on the roll in line with and passing close to 10 said projecting means on the breaker plate.

21. A structure as specified in claim 20, and other short teeth on the roll in line circumferentially with said long teeth, but too short to reach between said projections on the breaker plate.

CARL T. ANDERSON.
